UNITED STATES PATENT OFFICE.

JOHN BOYD AND THOMAS A. BOYD, OF SHETTLESTON, COUNTY OF LANARK,
SCOTLAND.

MACHINERY FOR WINDING YARN OR THREAD.

SPECIFICATION forming part of Letters Patent No. 236,767, dated January 18, 1881.

Application filed May 7, 1880. (No model.) Patented in Great Britain January 24, 1880.

To all whom it may concern:
Be it known that we, JOHN BOYD and THOMAS ALEXANDER BOYD, residing at Shettleston, in the county of Lanark, Scotland, and subjects 5 of the Queen of Great Britain, have invented certain Improvements in Machinery for Winding Yarn or Thread, (for which we have applied for British Letters Patent to be dated 24th January, 1880, No. 323,) of which the following is a specification.

Our invention relates to machines for winding yarn or thread singly or when doubling the same, in which machines detector-levers combined with stopping mechanism are used 15 for stopping the winding action on any one bobbin upon the breakage or failure of a yarn or thread. We improve the action of the detector-levers and render them more sensitive by making them of wood, and we apply to them 20 an adjustable balance-weight consisting of a metal helix which is held in position by a small stud, the helix being adjusted by screwing it relatively to the stud and being held securely by its spring resistance.

25 The guide or curl for the yarn or thread is a bent wire inserted into the end of the lever and through a piece of rubber tubing; the wire and tubing securing each other. When using sensitive detector-levers of our improved kind 30 it is more than ordinarily desirable to have irregularities in the tension of the yarn or thread compensated for or neutralized, so as to prevent the unrequired stopping action of the detector-levers, and this compensation must be effected, if possible, in a manner to suit the manner 35 in which the yarn or thread passes from its bobbin, cop, spindle, or other holder to the detector-lever.

40 The bobbins off which the yarns or threads are drawn are carried by hollow spindles or tubes set on spindles which are placed in inclined positions, being jointed to fixed points at a certain distance below the bobbins. Stationary frictional pieces are provided, against 45 which the bobbin or a part of the bobbin-holding spindle or tube rests by its weight, owing to its inclined position, when not turned upward therefrom by the tension of the yarn or thread as it is being drawn away. The tension 50 may lift the bobbin or its tube clear of the frictional piece, or it may only reduce its press-

ure on that piece. In either case the friction will have a compensating action, as it will increase when the tension becomes diminished, and vice versa. From cops the yarns pass 55 up to and over a rail, and thence proceed, in a nearly horizontal direction, to the detector-levers.

Our improvements are shown in the accompanying drawings.

60 Figure 1 is a transverse vertical section of a doubling winding-machine having similar winding mechanism along each side of it, but arranged for winding from bobbins at one side and from cops at the other side. Figs. 2 and 65 3 are an enlarged plan and sectional side elevation of the detector-lever. Figs. 4, 5, and 6 are a plan, sectional side elevation, and end elevation of the bobbin-compensating arrangement.

70 The yarns or threads are wound upon bobbins 6, which rest on drums 7, fixed on continuously-rotating longitudinal shafts 8, as in various well-known arrangements of doubling and winding apparatus. The bobbins 6 are 75 carried in holders 9, jointed to frame-brackets 10, and capable of being turned up by hand-levers 11. A slip-lever is used for stopping the driving action on any bobbin, 6, when a yarn or thread breaks or fails, such slip-lever being centered on a bracket, 12, fixed to a longitudinal center rail, 13. The slip-lever has a nearly-vertical arm or pair of arms, 14, to the upper end of which a slip, 15, of metal or other suitable material, is jointed, and a curved lower 80 arm, 16, extending beneath the winding-drum 7 toward the front, a balancing-weight, 17, being adjustable on a screwed projection at the back of the fulcrum.

85 The detector-levers 18 are carried on a wire 90 or spindle held in a small casting, 19, fixed to the under side of a longitudinal side rail, 20, and when any yarn or thread breaks or fails the inner end of its detector-lever 18, the weight of which is suitably adjusted for the purpose, 95 drops upon the front bent end of the lower slip-lever arm, 16, and makes that lever move so as to insert its slip 15 in between the winding-drum 7 and the bobbin, thereby stopping the winding action. Each detector-lever 18 100 consists of a light rod of wood, made with a boss perforated for the passage of the axial

wire. The inner end of the lever has a vertical cut formed in it, and a wire hook, 21, forming the guide for the yarn or thread, and having its shank bent at right angles, is entered up 5 the center of the lever, with its vertical part in the end cut, which keeps the hook in the vertical position. A piece of rubber tubing, 22, is placed on the end of the lever to be acted on by the winding-drum 7 when the lever 10 drops, so that the motion of the drum may hasten and enforce the descent of the lever and its action on the slip-lever. The wire hook or guide 21 is passed through the side of the piece of rubber tubing 22, and the hook and tubing thus serve to secure each other in place. 15

The detector-lever 18 is suitably balanced or poised by means of a metallic helix, 23, placed on its outer short end, being held in place by a small stud or pin fixed into the wood. The 20 helix is made with its coils so close that it is strained when it is screwed so as to have the stud between two coils, and it is adjusted by being screwed toward or from the fulcrum, as required, the tightness of the helix on the 25 wood and the elastic gripe of the coils on the stud preventing it from slipping out of place.

At the left-hand side of the machine the 30 yarns or threads pass to the hooks 21 of the detector-levers 18, directly from bobbins 24, and proceed up to elevated pulleys 25, thence 35 downward through the usual traverse-guide 26 to the bobbin 6.

Each bobbin 24 is, as shown more fully in 40 Figs. 4, 5, and 6, placed on a tube or hollow spindle, 27, formed with a collar or boss, 28, on its lower end, and set on a spindle, 29, which is, at its lower end, jointed to the bottoms of a pair of cheeks or small brackets, 30, extending down from a small casting, 31. 45 This casting 31 is fixed in an opening in the board 32, carrying the bobbins 24, and it is formed with a slot, through which the spindle 29 passes, and with a projection, 33, near the outer end of the slot, this projection serving as a stationary frictional piece.

The bobbin-board 32 is set at a slight inclination to throw the bobbin-spindles out of the vertical, and so that they may tend to lie with the collars or bosses 28 against the frictional 50 pieces 33, this inclination of the board being adjustable by turning the board on hinges which connect it to the side rail, 20, an arc-shaped bracket, 34, and screw-clamp 35 serving for fixing the board in any required position. The direction of the tension of the yarns or threads in proceeding from the bobbins 24 to the detector-levers 18 is such as to move the bobbins nearer the vertical position, and this 55 tension diminishes the pressure on the stationary frictional pieces, and consequently their resistance to the rotation of the bobbins and delivery of the yarn or thread. It is obvious that the frictional pressure will vary in-

versely with the tension, and that irregularities in the tension will thus be automatically compensated for, or nearly so, by the varying resistance. It will also be quite obvious that the same mechanical action will take place if the tension of the yarn or thread is opposed by weight or pressure acting in any manner 60 on the bobbin or its holder in a direction opposite to that of the tension, the bobbin and its holder being capable of moving in the direction of the tension or the opposite, and bearing more or less on a stationary frictional 65 piece accordingly.

At the right-hand side of the machine the 70 yarns pass upward from cops 36, through clearers 37, to a longitudinal guide-rail, 38, carried by the frame-rail 20, and they proceed round 75 the upper part of this rail 38, and thence inward to the hooks 21 of the detector-levers 18, whence they proceed as at the other side of the machine. Between the guide-rail 38 and the detector-hooks 21 there is a stationary 80 board, 39, having near its inner edge a covering of flannel or other frictional material, which each yarn touches whenever, through slackness, the inner end of its detector-lever 18 descends a little, and this increases the frictional resistance to the movement of the yarn, and in that 85 way compensates sufficiently for the slackness. But this arrangement of frictional surface for the threads to come into contact with we do not desire to claim in this case, as it will form 90 the subject of a separate application.

We claim as our invention—

1. The herein-described detector-lever, provided with a guide-hook, 21, and piece of rubber tubing at one end and an adjustable helical weight, 23, at the other, substantially as 95 set forth.

2. A detector-lever provided at one end with a pin or stud and a metal helix, 23, whose coils grip the said pin or stud, whereby the helix 100 may be adjusted on the end of the lever, substantially as described.

3. A detector-lever weighted at one end and carrying at the other end a wire hook, 21, having a bent end adapted to an end cut in the 105 lever and a rubber tube, 22, fitted over the end of the lever, all substantially as specified.

4. The combination of yarn-winding mechanism and a supporting-bracket with a bobbin-holding tube, 27, spindle 29, pivoted at an 110 angle, and the friction-piece 33, substantially 115 as and for the purpose set forth.

In testimony whereof we have signed our names to this specification in the presence of two subscribing witnesses.

JOHN BOYD.

THOMAS ALEXANDER BOYD.
